UNITED STATES PATENT OFFICE.

FRANCOIS JOSEPH DE SPOTURNO COTY, OF PARIS, FRANCE, ASSIGNOR TO COTY, INC.,
OF NEW YORK, N. Y., A CORPORATION OF DELAWARE.

DESIGN FOR A BOTTLE.

Application filed May 11, 1928. Serial No. 26,631. Term of patent 14 years.

To all whom it may concern:

Be it known that I, FRANCOIS JOSEPH DE SPOTURNO COTY, a citizen of the Republic of France, residing in the city of Paris, France, have invented a new, original, and ornamental Design for a Bottle, of which the following is a specification, reference being had to the accompanying drawing forming a part thereof.

In the drawing,

I claim:

The ornamental design for a bottle as shown.

FRANCOIS JOSEPH de SPOTURNO COTY.
